UNITED STATES PATENT OFFICE.

WALTER ELLERHORST, OF CINCINNATI, OHIO.

BARBER'S VACUUM HAIR RECEIVER.

Application filed September 4, 1926. Serial No. 133,672.

The present invention relates to what I call a barber's vacuum hair-receiver and aims to provide a device for creating a suction about the neck of a person having a hair-cut so as to suck the severed hairs away into a suitable receptacle.

As is well known, it is the present custom for barbers to place a cloth about the person receiving the hair cut which cloth is drawn tightly about the neck. Invariably hairs get down the neck and down the back of the person and furthermore the hairs fly all over the floor of the shop so as to necessitate frequent sweeping which causes considerable dust. raising and has numerous other detrimental features. The present invention does away with all these detrimental features besides having the further advantage of cooling the person receiving the hair-cut so as to prevent perspiration and allow the hair to be more efficiently cut with considerably greater comfort to the person receiving the hair-cut. Another very important object of the invention lies in the construction of a device of this nature, which is exceedingly simple, efficient and reliable in use, inexpensive to manufacture, easy to manipulate, light, strong, durable, and otherwise well adapted to the purpose for which it is designed. With the above and numerous other objects in view as will appear as the description proceeds, the invention resides in certain novelties of construction, and in the combination and arrangement of parts as will be hereinafter more fully described and claimed.

In the drawings:

Figure 1 is an elevation of my improved device showing the same associated with a 40. barber's chair,

Fig. 2 is a top plan view of the neck member,

Fig. 3 is a sectional view therethrough.

Referring to the drawing in detail, it will be seen that the numeral 5 denotes the bottom or seat portion of a barber's chair which is supported on the usual standard structure 6 and the numeral 7 denotes the back of the chair. All of these parts may be of any conventional or preferred construction and are illustrated herein merely for the purposes of example. A vacuum cleaner suction-creating device 8 of any well-known construction is supported below the seat 5 and has associated therewith the usual well-known bag receptacle 9. An oblong spout

extends from the suction-creating device 8 and a flexible hose 11 is engaged therewith by a suitable coupling 12. A coupling 14 is provided at the upper end of the hose 11. 60. This hose 11 may be formed in a large number of sections, if desired, for making the device adjustable.

The numeral 15 denotes a neck can which has an opening 16 in the bottom thereof and a larger opening 17 in the top thereof and is formed with an elbow spout 18 which engages with the hose as at 14. A sleeve 19 is riveted or otherwise fastened to the bottom of the can 15 as is indicated at 20 and 70 extends upwardly through the opening 17. This sleeve 19 is preferably constructed of rubber although any other flexible elastic material will be suitable for this purpose. The sleeve 19 is passed over the head of the 75 person having the hair-cut until the can rests on the person's shoulder. The sleeve 19 should be sufficiently tight to prevent hair from falling down the neck inside the sleeve.

When the suction-creating device 18 is turned on, it will be seen that all the severed hairs will be sucked into the can 15 down the spout 18 down the tube 20 through the suction-creating device 18 into the bag or other like receptacle 9. There is practically no 80 likelihood of any of the severed hairs escaping a device of this nature and it will also be seen that it constantly creates a current of air about the head of the person receiving the hair cut so as to keep said head comparatively cool and thus prevent the usual accumulation of perspiration in hot weather.

The present embodiment of the invention has been disclosed in detail since in actual practice it has attained the features of advantage enumerated as desirable in the statement of the invention. It is quite apparent, however, that numerous changes in the design of the parts, the details of construction, and the combination and arrangement of the 100 parts may be resorted to without departing from the spirit or scope of the invention as hereinafter claimed or sacrificing any of its advantages.

Having thus described my invention, what I claim as new is:

1. A device of the class described including a pan having a spout extending therefrom adapted to be connected with a vacuum creating means, said pan being provided 110 with an opening in the bottom thereof and a larger opening in the top thereof.

2. A device of the class described, including a pan having a spout extending therefrom adapted to be connected with a vacuum creating means, said pan being provided
5 with an opening in the bottom thereof and a larger opening in the top thereof, a flexible sleeve fixed in the bottom about the opening and adapted to extend through the opening in the top.
- 10 3. A device of the class described, including a pan having a spout extending there-

from adapted to be connected with a vacuum creating means, said pan being provided with an opening in the bottom thereof and a larger opening in the top thereof, a flexible 15 sleeve fixed in the bottom about the opening and adapted to extend through the opening in the top, said flexible sleeve being constructed of elastic material.

In testimony whereof I affix my signature.

WALTER ELLERHORST.
